DESIGN.

—o—

J. H. HANKINSON.
ANDIRON.

No. 17,168.

Patented Mar. 8, 1887.

UNITED STATES PATENT OFFICE.

JOHN H. HANKINSON, OF NEW YORK, N. Y.

DESIGN FOR AN ANDIRON.

SPECIFICATION forming part of Design No. 17,168, dated March 8, 1887.

Application filed July 9, 1885. Serial No. 171,122. Term of patent 7 years.

To all whom it may concern:

Be it known that I, JOHN H. HANKINSON, a citizen of the United States, residing at New York, in the county and State of New York, have invented and produced a new and original Design for Andirons, of which the following is a specification, reference being had to the accompanying drawing, forming part thereof.

10 The figure represents a front elevation of my newly-designed andirons, exhibiting the ornamentation thereon.

The leading features of this design consist of the representation of an owl's head, *a*, at the 15 top of a vertical standard, *b*, with ribbon *c* on either side below the owl's head, the vertical

standard *b* being dotted at intervals with button rosettes, between which appears scroll-work. The arched base or legs *d* are curved, and present similar ornamentation to that shown upon 20 the face of the standard.

I claim—

The arched base or legs *d* and vertical standard *b*, with raised buttons and scroll-work, crowned with the representation of an owl's 25 head, with ribbons *c* at the sides of the standard, as herein shown and described.

JOHN H. HANKINSON.
